• C. T. GROSJEAN.
SPOON, OR ANALOGOUS ARTICLE.

No. 15,715.

Patented Jan. 13, 1885.

Fig. 1

UNITED STATES PATENT OFFICE.

CHARLES T. GROSJEAN, OF NEW YORK, N. Y., ASSIGNOR TO TIFFANY & CO.,
OF SAME PLACE.

DESIGN FOR A SPOON OR ANALOGOUS ARTICLE.

SPECIFICATION forming part of Design No. 15,715, dated January 13, 1885.

Application filed October 14, 1884. Term of patent 14 years.

To all whom it may concern:

Be it known that I, CHARLES T. GROSJEAN, a citizen of the United States, residing in the city, county, and State of New York, have invented and produced a new and original Design for Spoon-Handles or other Articles of Table-Service, of which the following is a specification, reference being had to the accompanying drawings, forming part thereof.

10 The shank of this spoon-handle is an unbroken line commencing at a leaf next and immediately above the bowl up to the head, which head is broken in outline by its ornament. The design of head of the handle embraces a 15 family coat of arms with the crest in high relief, filling the whole of the head. Extending from this head down the shank between the unbroken lines are male and female figures, emblems, and leaves in relief. The reverse surface of the handle has on the head an edge of scroll conforming to the outline on the front surface and inclosing emblems of the chase, such as stag's head, &c. Down the shank between the unbroken lines are bunches 25 of laurel-leaves to a point where the shank joins the rounded part of the bowl of the spoon. At this point it joins an ornament representing the head, skin, and feet of a leopard.

In the drawings, Figure 1 is a view of the 30 front surface of a spoon-handle and its bowl on which is placed my design. Fig. 2 is a view of the reverse surface or back thereof.

The design of front and back is equally applicable to a fork-handle.

35 *a* is the unbroken line of the shank, terminating at the head. This head contains on its front surface, Fig. 1, the family coat of arms and crest *b* in high relief, the whole outline being more or less broken. Between the unbroken lines on the shank are male and female figures, *c c'*, in a reclining position, surrounded with emblems and leaves, all in relief. On the back, Fig. 2, the head has an edge of scroll-work, *d d*, broken in outline, so as to 40 conform to the outline on the front of the

head. There is inclosed between its scroll-work emblems of the chase—such as a stag's head, horn, &c.—*e e'*. There may be seen in Fig. 2, in the upper part of the head, a monogram. Between the unbroken lines *a*, which 50 inclose the shank, are bunches of laurel-leaves *f f* down to and ending at a point where the shank joins the rounded part of the bowl of spoon. At this point an ornament, *g*, representing the head, feet, and skin of a leopard, 55 is placed.

I claim—

1. A design for a spoon-handle of the shape shown, consisting of unbroken outline of head representing a coat of arms and crest in high 60 relief, and an unbroken outline of shank in which are placed reclining male and female figures, emblems, and leaves in relief, as shown and described.

2. A design for a spoon-handle of the shape 65 shown, consisting on its reverse surface of an unbroken outline of head containing scroll-work, between which scroll-work are placed emblems of the chase, as shown and described.

3. A design for a spoon-handle of the shape 70 shown, consisting on its reverse surface of an unbroken outline of head containing scroll-work, between which scroll-work are placed emblems of the chase, and a shank unbroken in its outline, containing bunches of laurel-leaves, 75 as shown and described.

4. A design for a spoon-handle of the shape shown, consisting on its reverse surface of an unbroken outline of head containing scroll-work, between which scroll-work are placed 80 emblems of the chase, and a shank unbroken in its outline, containing bunches of laurel-leaves, ending in an ornament representing the head, skin, and feet of a leopard, as shown and described.

CHARLES T. GROSJEAN.
